UNITED STATES PATENT OFFICE.

ARTHUR RONALD TRIST, OF ST. ALBANS, ENGLAND, ASSIGNOR TO TRIST PIANO
PLAYER LIMITED, OF LONDON, ENGLAND.

MUSIC-RECORD SHEET FOR AUTOMATIC PIANO-PLAYING MECHANISMS AND THE LIKE.

941,433.

Specification of Letters Patent. Patented Nov. 30, 1909.

Original application filed November 10, 1906, Serial No. 342,891. Divided and this application filed December 11, 1907. Serial No. 406,032.

To all whom it may concern:

Be it known that I, ARTHUR RONALD TRIST, a subject of the King of Great Britain and Ireland, residing at St. Albans, Hertfordshire, England, have invented new and useful Improvements in Music-Record Sheets for Automatic Piano-Playing Mechanism and the Like, of which the following is a specification.

10 This invention relates to music record sheets for automatic piano playing mechanism and the like and has for its object the provision of means on the record sheet whereby the accentuation of specific notes 15 in any composition is effected in a simple manner. In connection with each note of the piano playing mechanism I provide an electromagnet or solenoid or other equivalent device which is energized by an electric 20 current and is controlled in its action by the music sheet itself.

In order that my invention may be the better understood I will now proceed to describe the same in relation to the accompanying drawing reference being had to the 25 letters marked thereon.

Like letters refer to like parts in both figures.

Figure 1 is an underside plan of my form 30 of music record sheet. Fig. 2 is an exaggerated sectional view of the same.

Referring to Figs. 1 and 2 it will be noticed that the music record sheet consists of the ordinary perforated tune sheet *w* having a layer *x* of tin foil or other electrical conductor attached thereto. A backing of paper *y* is applied to the tin foil in order to protect the same, an exposed strip *z* of tin foil being arranged at the edge of a music 35 record sheet on which the roller bears so as to complete an electric circuit through the record sheet. It is obvious that the backing layer *y* may be omitted without interfering with the function of the sheet, it being only necessary for protective purposes from mechanical injury of the tin foil or other metallic layer.

The paper layer *w* of the record sheet is perforated in the ordinary way and with the

ordinary perforations *w*¹ which are wholly obscured by the tin foil layer *x* which forms the only means for actuating loud notes which form the melody and which are to be accentuated. The perforations *w*² right through the record sheet are at the leading end of the note perforations and permit the air to enter the particular orifice in the tracker so that the said notes (say forming the accompaniment) are struck softly and the notes on being struck are held on by the electric circuit being completed by the tin foil which is exposed by the continuation of the perforations *w*³ as provided in the ordinary music sheet. It will be thus seen that when a perforation comes over the tracker and the ordinary valves of the pneumatic action are operated in the usual manner, the duration of the particular note struck by means of the governed vacuum can be controlled either by the length of complete perforation or by the exposed foil in the perforation. In this way any note unperforated can be perforated at will by a person desiring such note to be softened in addition to the original perforations provided on the sheet. When an unperforated note viz: one where the tin foil only is exposed, occurs the electrical circuit is completed, the orifice in the power pneumatic is put into direct communication with the high vacuum of the reservoir thus causing the power pneumatic to strike a hard or loud note. It will be readily understood that the function of the perforated and non-perforated parts of the record sheet together with the corresponding mechanism controlled by same can be reversed viz: the hard notes can be produced by the perforated notes and the soft notes by the tin foil or non-perforated notes.

It is obvious that the high vacuum can be regulated or controlled by the usual mechanism if thought desirable.

Having now described my invention, what I claim and desire to secure by Letters Patent is:—

A record music sheet for pneumatic piano playing apparatus having a non-conducting layer perforated with all the note perfora-

tions in combination with a conducting layer having through perforations for selected notes arranged at the end of the note perforations of the non-conducting layer adapted
5 to control the striking of the selected notes in distinction to the other notes initially operated by the non-perforated conducting layer.

In testimony whereof I have signed my name to this specification in the presence of 10 two subscribing witnesses.

ARTHUR RONALD TRIST.
